UNITED STATES PATENT OFFICE.

CHARLES I. BAKER, OF ORLAND, CALIFORNIA.

PORTABLE SHELTER.

Application filed February 6, 1922. Serial No. 534,615.

To all whom it may concern:

Be it known that I, CHARLES I. BAKER, a citizen of the United States of America, residing at Orland, in the county of Glenn and 5 State of California, have invented certain new and useful Improvements in Portable Shelters; and I do hereby declare that the following is a full, clear, concise, and exact description of the same, such as will enable 10 others skilled in the art to which it appertains to make and use the same.

This invention relates to improvements in portable shelters, having for an object to provide a combined shelter and bed especially desirable for use by campers, whereby they may erect a temporary shelter which will afford a bed or support and in addition thereto, ample space for dressing, cooking, eating or other purposes.

20 It is likewise an object of the invention to provide a shelter of the character mentioned which is of knock-down design, whereby to permit of packing or placing the same in a confined or limited space and 25 by consequence, rendering the device especially advantageous for use by automobile tourists, whose equipment, in its essentials must be of such character as to occupy but minimum space during transportation.

30 Another object of the invention is to provide the device with a novel form of frame having portions thereof arranged to permit the ready constructing of a bed or similar support.

35 Other objects will be in part obvious and in part pointed out hereinafter.

In order that the invention and its mode of operation may be readily understood by persons skilled in the art, I have in the accompanying illustrative drawings and in the detailed following description based thereon, set out one possible embodiment of the same.

In these drawings:

Figure 1 is a perspective view of a portable shelter constructed in accordance with this invention.

Figure 2 is a view of the frame of such a shelter, the view being in perspective.

Figure 3 is an end view of the shelter 50 showing the bed arrangement therefor.

Figure 4 is a plan view of the bed.

Figure 5 is an enlarged detail view of one end of the bed, the view being partly in section and partly in elevation.

55 Figure 6 is a view similar to Figure 5 but showing the central joints of the bed.

Figure 7 is a detail view of the joint arranged between three of the frame members.

Figure 8 is a view of the preferred form of mattress used herewith.

Figure 9 is a detail view showing one of the buttons for securing the cover of the shelter on its frame.

In the accompanying drawings it will be seen that there is provided an upper longitudinal frame member 1 which is made in sections connected by a T-joint 5 and that extending downwardly from the ends and middle of this frame member are jointed supports 3, the joints of these supports 70 being likewise connected by T-joints as at 5, or by a straight joint as at 5'. Extending downward from the corner posts 3 are top end frame members 6 which are also made in sections, the sections being connected by T-joints 5 and at the lower ends of the members 6 are elbows 4 which are supported on jointed standards 3', the joints 5 of the slanting end members 6 being supported on similar standards 3' but of greater length. 80 Extending between rear corners of the standards 3' is a rear bed frame member 12 and between the intermediate standards 3' is a similar bed frame member 12. The end frame members 13 connect corner standards 85 3' with the intermediate standards 3' and also thus connecting the members 12. These members 12 are jointed and are connected by T-joints 14 supported on legs 15.

A horizontally and longitudinally disposed section 8 is connected to certain of the vertical sections 3 through the medium of T-slip joint connections 5 and provides therebelow ample space for an entrance or doorway to the shelter.

Over the frame of the shelter or the supporting structure, a fabric covering or envelope is placed, such as indicated in dotted lines by the numeral 9, said covering or envelope being provided with an inclined top 100 and vertical front, rear and end walls, the front wall thereof, of course, being partly cut away to correspond to that space occurring below the horizontal section 8 and the vertical section 3 interconnected by the same 105 for an obvious purpose. In order that the envelope 9 may be secured to adjacent portions of the various sections of the supporting frame, I may and preferably do arrange upon those portions of the frame section 110 contacting with the envelope studs generally indicated by the numeral 10, which as will

be noted, are adapted to be releasably engaged in eyelets 11 secured to the inner sides of adjacent portions of such envelope. By this mode of connection between the envelope and the same, it will be readily appreciated that undue movement therebetween will be prevented to a material extent, such for example, as with flapping of the fabric envelope against adjacent portions of 10 the supporting frame during windy or stormy conditions.

Within the supporting frame, I arrange other longitudinal and transverse sections of tubing or similar material indicated by the 15 numerals 12 and 13, constituting thereby a horizontally arranged rectangular frame, the longitudinal portions of which are in sections and connected by T-slip joints 14, similar to the joints 5 whereby supporting 20 legs 15 can be engaged in their vertical portions for effectually supporting the intermediate parts of said longitudinal sections 13.

Over the rectangular frame constituted by 25 the sections 12 and 13, a heavy fabric envelope or cover 16 is arranged, having top, side and end walls of suitable design. Longitudinally disposed slats 17 are provided the rectangular frame and as will be noted, 30 are formed in sections, the adjacent ends of which are connected by hinges 18, while hooked metal arms 19 are secured to the opposite end portions thereof through the medium of bolts 20 or similar fastening devices and are adapted to have the curved or 35 hooked ends 19' thereof snugly engaged over adjacent portions of the transverse sections 13. Thus, when a plurality of these hinged sectional slats 17 are arranged in juxtaposed 40 relation upon the rectangular frame, an effectual bed or similar support will have been provided; the same lying directly over the top of the heavy fabric envelope 16 and by consequence, preventing a person lying 45 or supported thereon from the inconvenience of dirt, dust, or the like.

A mattress 21 is preferably provided the slats 17 and as will be noted, is divided longitudinally as at 22 in order that the outer 50 section thereof may be swung downwardly at those times when it is desired to use but a portion of the bed, as for example during day time, when it is desirable to secure all available space within the shelter. Upon 55 such occasions, a number of the slats 17 may be removed from the rectangular frame, leaving only the rearwardly disposed slats and by consequence, permitting the outer section of the mattress 21 to drop down- 60 wardly, thus affording what may be aptly termed as a day bed.

If desirable, the hooked arms 19 may be formed of spring metal, whereby to add to the resiliency of the hinged sectional slats 17.

From the foregoing, it will be understood that I have provided a simple but highly efficient form of temporary shelter which will be found to be especially desirable for use by campers, automobile tourists and 70 similar parties. Because of the sectional or knock down arrangement of the supporting frame structure, the various longitudinal, transverse and vertical sections thereof, with disassembly, may be compactly arranged in 75 a comparatively small bundle, which in turn, can be stored or placed in a confined or limited space. Should the device be used by automobile tourists, it is manifest, that the same in its disassembled and compact form may be arranged upon the running board 80 of the automobile or in the luggage carrying compartment thereof as may be desired.

Because of the arrangement of the bed supporting means within the frame, ample 85 space is provided for its occupant or occupants to dress, cook, eat, et cetera; additional space being available by modifying the arrangement of the slats 17 together with the mattress 21, as hereinbefore stated.

Manifestly, the construction shown is 90 capable of considerable modification and such modification as is within the scope of my claims, I consider within the spirit of my invention.

I claim:

1. In combination, a main frame including quadrilaterally disposed vertical members, horizontally disposed bed frame members connected to said vertically disposed members, a fabric cover stretched over a pair of the horizontally disposed members and slats having hooked ends engaging over said pair of members and clamping the cover thereto.

2. In combination, a main frame including quadrilaterally disposed vertical members, horizontally disposed bed frame members connected to said vertically disposed members, a fabric cover stretched over a pair of the horizontally disposed members and slats having hooked ends engaging over said pair of members and clamping the cover thereto, said slats having hinges on their lower sides at their central portions resting on said fabric cover whereby the fabric cover assists in supporting said hinge joint.

In witness whereof I have hereunto set my hand.

CHARLES I. BAKER.
